UNITED STATES PATENT OFFICE.

GEORGE D. HAWLEY, OF LOWELL, MASSACHUSETTS.

SPOOL HOLDER.

Application filed April 27, 1927. Serial No. 186 939.

This invention relates to a spool or bobbin holder and has for its object to provide, in a manner as hereinafter set forth, a simple, inexpensive, strong, durable, compact and thoroughly efficient device of such class for holding or racking a series of spools or bobbins.

A further object of the invention is to provide, in a manner as hereinafter set forth, a device of such class including a skeleton base 10 provided with two oppositely extending sets of spaced strips, and with the strips of one set alternately extending above and below the strips of the other set in abutting relation, and with the abutting portions of the 15 strips secured together by pins extending through and projecting from said abutting portions to provide spool or bobbin retainers.

A further object of the invention is to provide, in a manner as hereinafter set forth, a 20 spool or bobbin holder constructed throughout of metal whereby it will be capable of withstanding the severe usage to which devices of this type are subjected.

With the foregoing and other objects in 25 view the invention consists of the novel construction, combination and arrangement of parts as hereinafter more specifically described and illustrated in the accompanying drawings wherein is shown an embodiment of 30 the invention, but it is to be understood that changes, variations and modifications can be resorted to which fall within the scope of the claims hereunto appended.

In the drawings wherein like reference 35 characters denote corresponding parts throughout the several views:

Figure 1 is a top plan view of the spool or bobbin holder.

Figure 2 is an inverted plan thereof.

Figure 3 is a section on line 3—3, Figure 1.

Figure 4 is a sectional view on the line 4—4 of Figure 1.

Figure 5 is a fragmentary view, in perspective, upon an enlarged scale of the holder.

Figure 6 is a section on line 6—6, Figure 2.

A spool or bobbin holder, in accordance with this invention, is constructed throughout of metallic material and comprises a frame 1 preferably of polygonal contour and 50 which has positioned against its lower face or rather inner face, at each corner thereof, a corner piece 2. The frame 1 includes four frame members 3, 4, 5 and 6 which preferably are integral with each other and is so shown. At the point of joinder of the frame members with each other, openings 5' are provided and

each opening 5' is positioned between an inner and an outer corner 7, 6' respectively of the frame. The corner 7 is squared and the corner 6' rounded. The frame member 3 is 60 formed with a row of equally spaced openings 8. The frame member 4 is provided with a row of equally spaced openings 9. The frame member 5 is provided with equally spaced openings 10 and the frame member 6 is 65 formed with a row of equally spaced openings 11. The openings 5' are equally spaced from the rows of openings 8, 9, 10 and 11. Each corner piece 2 is formed with an opening 12 which registers with an opening 5'. The corner pieces are flush with the edge of the frame 1 at the points of joinder of the frame members with each other.

Connected to the frame 1 are two oppositely disposed sets of spaced strips. One set is connected to the frame members 3, 6 and the other set is secured to the frame members 4, 5. The sets of strips are secured against the inner or lower face of the frame 1. The strips of each set are equally spaced with respect to each other and the outer strip of each set are spaced the same distance from the frame members as the distance between the strips of the set. The strips of the set which are secured to the frame members 3, 6 are indicated at 13 and 85 the strips of the set which are secured to the frame members 4, 5 are indicated at 14.

The strips of one set extend at right angles with respect to the strips of the other set. Each end of each of the strips of each 90 of the sets is formed with an opening 15. The openings 15 at one end of the strips 13 register with the openings 8 and the openings 15 at the other end of the strips 13 register with the openings 11. The openings at one 95 end of the strips 14 register with the openings 9 and the openings 15 at the other end of the strips 14 register with the openings 10. Each strip 13 is formed with a series of 100 equally spaced upset portions 16. The upset portions 16 of one strip 13 are staggered with respect to the upset portions of an adjacent strip 13. The upset portions of one strip 13 are arranged in a plane centrally with respect to a pair of upset portions 16 of 105 an adjacent strip 13. Each strip 14 is formed with a series of equally spaced upset portions 17 substantially of inverted U-shape and with the upset portions 17 of one strip 14 staggered with respect to the upset portions 17 of an adjacent strip 14. The upset portions 17 of one strip 14 are disposed cen-

trally in a plane with respect to a pair of upset portions 17 of an adjacent strip 14. The openings 8 and 11 are arranged in alignment with each other and are disposed in a plane centrally with respect to the upset portions 17. The openings 9 and 10 are arranged in alignment and are disposed in a plane centrally with respect to the upset portion 16. The strips 13 extend through the upset portions 17 and abut the strips 14. The strips 14 extend through the upset portion 16 and abut the strips 13.

Each of the strips 13 is formed with a series of equally spaced substantially U-shaped depressed portions 18 and the depressed portions 18 of one strip 13 are disposed in a plane centrally with respect to a pair of depressed portions 18 of an adjacent strip 13. Each of the strips 14 is formed with a series of equally spaced depressed portions 19 and the depressed portions 19 of one strip 14 are positioned in a plane centrally of a pair of depressed portions 19 of an adjacent strip 14. The depressed portions 18 of one strip 13 are staggered with respect to the depressed portions 18 of an adjacent strip 13. The depressed portions 19 of one strip 14 are staggered with respect to the depressed portions of an adjacent strip 19. The strips 13 extend through the depressed portions 18 and abut against the strips 14. The strips 14 extend through the depressed portions 18 and abut against the strips 13.

Each of the upset portions of each of said strips is provided with an opening 20 and each of the depressed portions of each of said strips is formed with an opening 21. The strips 13 are provided with spaced openings 22 and the strips 14 with spaced openings 23. The openings 22 of the strips 13 register with the openings 20 of the strip 14 and the openings 23 of the strips 14 register with the openings 21 of the strip 13.

The ends of the strips of each of said sets 45 are positioned against the inner or lower faces of the frame members, and the corner pieces 2 are the same thickness as the ends of the strips to provide for the base of the device to evenly seat upon a support. The 50 base of the device is formed by the frame 1 and the two sets of strips. The upset and depressed portions provide for the strips of one set to alternately extend above and below the strips of the other set in abutting relation and the abutting portions of the strips 55 are secured together by pins referred to generally by the reference character 24 and each of which consist of a cylindrical shank 25, provided at its lower end with a head 26 and having its upper end rounded as at 27. The 60 pins 24 not only provide means for connecting the strips of one set with the strips of the other set in spaced relation, to secure said strips together, but further provide spool or bobbin retainers, as the shanks 25 of the

pins are of a desired length to project a substantial distance above the base for the purpose of receiving the spool or bobbin. Owing to the disposition of the upset and depressed portions of the strips, with respect to each other, the pins 24 are equally spaced from each other. The pins are arranged in horizontal and transverse rows and the heads thereof alternately engage the strips 13 and 14. 75

The ends of the strips of the said sets and also the corner pieces 2, are secured to the frame members by pins 27 formed of a shank 28, a head 29 at the lower end of the shank 28 and with the upper end of the latter rounded at 30. The pins 27 perform the same function as the pins 24 with respect to the spools or bobbins, and further as before stated act as a means to secure the strips of both sets and also the corner pieces to the frame members. The heads 29 of certain of the pins 28 abut against the corner pieces 2 and the heads of the remaining pins 27 abut against the lower faces of the strips at the ends thereof. The pins 24 and 27 are secured in position, 90 in any suitable manner preferably by welding. The heads of the pins 27 which are arranged below the frame members 4, 5 abut against the ends of the strips 14 and also the corner pieces 2. The heads of the pins 27 which are arranged below the frame members 3, 6 abut against the strips 13. 95

It is thought the many advantages of a spool or bobbin holder or rack, in accordance with this invention, can be readily understood, and although the preferred embodiment of the invention is as illustrated and described, yet it is to be understood that changes in the details of construction can be had which will fall within the scope of the 105 invention as claimed.

What I claim is:

1. A spool or bobbin holder comprising a frame, a pair of oppositely disposed sets of spaced strips positioned against the inner face of the frame and extending completely across the opening formed thereby, each of said strips provided with alternately disposed upset and depressed portions, the upset portions being spaced from the depressed portions, said upper portions being of inverted U-shape and said depressed portions being U-shape, the strips of one set extending through the upset and depressed portions of and abutting the strips of the other set, stationary retainer elements extending through and projecting from the abutting portions of the strips of said sets for securing said strips together, and stationary retainer elements extending through the ends of the strips and the body of the frame for securing them together and further projecting from the frame. 115

2. A spool or bobbin holder comprising a frame, a pair of oppositely disposed sets of spaced strips positioned against the inner 120

face of the frame and extending completely across the opening formed thereby, each of said strips provided with alternately disposed upset and depressed portions, the upper set portions being spaced from the depressed portions, said upper portions being of inverted U-shape and said depressed portions being U-shape, the strips of one set extending through the upset and depressed portions of and abutting the strips of the other set, stationary retainer elements extending through and projecting from the abutting portions of the strips of said sets for securing said strips together, stationary retainer elements extending through the ends of the strips and the body of the frame for securing them together and further projecting from the frame, each of said retainer elements having a head at its lower end and a rounded upper end, said heads abutting against the said strips.

3. A spool or bobbin holder comprising a frame, a pair of oppositely disposed sets of strips positioned against the inner face of the frame and extending completely across the opening formed thereby, each of said strips provided with alternately disposed upset and depressed portions, the upset portions being spaced from the depressed portions, said upper portions being of inverted U-shape and said depressed portions being U-shape, the strips of one set extending through the upset and depressed portions of and abutting the strips of the other set, retainer elements extending through and projecting from said abutting portions of the strips of said sets for securing said strips together and further having their lower ends abutting against the lower faces of the strips, corner pieces positioned against the inner face of said frame at each corner thereof, stationary retaining elements extending through the ends of said strips and body of the frame for securing them together and further extending from the frame, and having their lower ends abutting against the lower faces of the strips, stationary retaining elements extending through the ends of said strips and body of the frame for securing them together and further projecting from the frame, each of said retaining elements having a head at its lower end and a rounded upper end, said heads abutting against the lower faces of the strips.

4. A spool or bobbin holder comprising a frame, a pair of oppositely disposed sets of strips positioned against the inner face of the frame and extending completely across the opening formed thereby, each of said strips provided with alternately disposed upset and depressed portions, the upset portions being spaced from the depressed portions, said upper portions being of inverted U-shape and said depressed portions being U-shape, the strips of one set extending through the upset and depressed portions of and abutting the strips of the other set, retainer elements extending through and projecting from said

abutting portions of the strips of said sets for securing said strips together and further having their lower ends abutting against the lower faces of the strips, corner pieces positioned against the inner face of said frame at each corner thereof, stationary retaining elements extending through the ends of said strips and body of the frame for securing them together and further extending from the frame, and having their lower ends abutting against the lower faces of the strips, stationary retaining elements extending through the ends of said strips and body of the frame for securing them together and further projecting from the frame and having their lower ends abutting against the lower faces of the strips, stationary retaining elements extending through the ends of said strips and body of the frame for securing them together and further projecting from the frame and having their lower ends abutting against the lower faces of the strips, each of said retaining elements having a head at its lower end and a rounded upper end, said heads abutting against the lower faces of the strips and against said corner pieces.

5. A spool or bobbin holder comprising a frame having the members thereof flat, a pair of oppositely disposed sets of spaced, flat strips having their ends positioned against the inner faces of said members and extending completely across the opening formed by the frame, each of said strips provided with alternately disposed upset and depressed spaced portions, the upset portions spaced from the depressed portions, the strips of one set extending through the upset and depressed portions of and abutting the strips of the other set, said abutting portions provided with registering openings, vertical pins extending through and projecting above said registering openings and secured to said strips, and vertical pins extending through the ends of the strips and the frame members, secured therewith and further projecting from the frame.

6. A spool or bobbin holder comprising a frame having the members thereof flat, a pair of oppositely disposed sets of spaced, flat strips having their ends positioned against the inner faces of said members and extending completely across the opening formed by the frame, each of said strips provided with alternately disposed upset and depressed spaced portions, the upset portions spaced from the depressed portions, the strips of one set extending through the upset and depressed portions of and abutting the strips of the other set, said abutting portions provided with registering openings, vertical pins extending through and projecting above said registering openings and secured to said strips, vertical pins extending through the ends of the strips and the frame members, secured therewith and further projecting from the frame, and said pins providing for securing said strips together and for securing said strips to the frame members.

7. A spool or bobbin holder comprising a frame having the members thereof flat, a pair

of oppositely disposed sets of spaced, flat strips having their ends positioned against the inner faces of said members and extending completely across the opening formed by the frame, each of said strips provided with alternately disposed upset and depressed spaced portions, the upset portions spaced from the depressed portions, the strips of one set extending through the upset and depressed portions of and abutting the strips of the other set, said abutting portions provided with registering opens, vertical pins extending through and projecting above said registering openings and secured to said strips, vertical pins extending through the ends of the strips and the frame members, secured therewith and further projecting from the frame, corner pieces mounted on said frame at the junction of the frame members, and vertical pins extending through said corner pieces and the corners of the frame and secured therewith.

8. A spool or bobbin holder comprising a frame having the members thereof flat, a pair of oppositely disposed sets of spaced, flat strips having their ends positioned against the

inner faces of said members and extending completely across the opening formed by the frame, each of said strips provided with alternately disposed upset and depressed spaced portions, the upset portions spaced from the depressed portions, the strips of one set extending through the upset and depressed portions of and abutting the strips of the other set, said abutting portions provided with registering opens, vertical pins extending through and projecting above said registering openings and secured to said strips, vertical pins extending through the ends of the strips and the frame members, secured therewith and further projecting from the frame, said pins providing for securing said strips together and for securing said strips to the frame members, corner pieces mounted on said frame at the junction of the frame members, and vertical pins extending through said corner pieces and the corners of the frame and secured therewith.

In testimony whereof, I affix my signature hereto.

GEORGE D. HAWLEY.
